Inventor

Richard W. McQueary.

By Attorney

UNITED STATES PATENT OFFICE.

RICHARD W. MCQUEARY, OF GRAND LAKE, COLORADO.

CULVERT.

Application filed July 16, 1921. Serial No. 485,364.

To all whom it may concern:

Be it known that I, RICHARD W. MCQUEARY, a citizen of the United States, residing at Grand Lake, Colorado, have invented certain new and useful Improvements in Culverts; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to open top road drainage culverts and is an improvement on the culvert described and claimed in Patent No. 1,362,952 granted to me on December 21, 1920.

The object of this invention is to produce a culvert of an improved design that can be more readily constructed and that can be made and installed with a minimum expense and labor.

In order to more clearly describe my improved culvert I shall refer to the accompanying drawings in which

Fig. 1 is a plan view of the tubular part of my culvert.

Fig. 2 is a section taken on line 2—2

Fig. 1.

Fig. 3 is a plan view of the angle flanges.

Fig. 4 is a side view of the angle flanges.

Fig. 5 is a section taken on line 5—5, Figs. 3 and 4.

Fig. 6 is a cross section of my culvert installed in place in the road.

The same reference characters represent the same parts throughout the several views.

The tubular member 1 has a slot 2 throughout its entire upper surface and the ends are provided with projecting portions 3 whose function it is to extend to the side of the roadbed and direct the water from the gutter into the culvert.

My culvert is designed to be placed across the road with the open slot 2 at top so that any surface drainage water will flow through the slot and directly into the culvert.

In order to make the culvert of sufficient strength to resist the impact due to heavy traffic and also to provide a smooth, flat surface for the vehicles to cross I have provided a pair of flanges, 4 4 which extend outwardly from the edges of said slot. The flanges are made separate from the tubular part and are slid into the slot and held in place therein by means hereinafter described.

My removable flanges comprise two angle irons 5 and 6 which are united along one side by means of rivets 7, the two sides being held spaced by means of short ferrules 8. The heads 9 of the rivets serve to retain the flanges in place on the culvert as shown in Fig. 6.

The culvert is placed in position in the road bed 10 in the manner shown in Fig. 6: the material of the road bed being tamped firmly against the culvert and the upper surface thereof being on a level with the upper surface of the flanges 4.

On account of the strong and rigid construction of my removable flanges I find that it is unnecessary to embed the culvert in concrete as has heretofore been done: this results in a large saving where many culverts are installed. The flanges being separate and removable from the tubular portion of my culvert makes it easier to handle and to install and as the flanges are so designed that the rivets are freely accessible, the assembling can be done with a minimum amount of work and expense.

Having thus described my invention what I claim is:

A culvert comprising a cylindrical metal member split longitudinally along its upper side to form a narrow slot, removable horizontally extending flanges secured in said slot, said flanges comprising two angle irons placed back to back and held in spaced relation, said spaced sides being slidably connected to said cylindrical member.

In testimony whereof I affix my signature.

RICHARD W. MCQUEARY.
